WRITING INSTRUMENT DESK SET BASE

Donald W. Doman, Janesville, Wis., assignor to The Parker Pen Company, Janesville, Wis., a corporation of Wisconsin

Application September 20, 1957, Serial No. 47,787

Term of patent 14 years

(Cl. D74—1)

Fig. 1 is a perspective view of a writing instrument desk set base, showing my new design;
Fig. 2 is a top plan view thereof;
Fig. 3 is a side elevational view thereof;
Fig. 4 is an end elevational view thereof; and
Fig. 5 is a sectional view thereof, taken along line 5—5 in Fig. 2.

I claim:

The ornamental design for a writing instrument desk set base, substantially as shown.
